[57] **CLAIM**

The ornamental design for a combined door and frame structure, as shown.

DESCRIPTION

FIG. 1 is a perspective view of a combined door and frame structure taken from a point forwardly of and upwardly to the left of the forwardly facing front surface of the door and frame structure.

FIG. 2 is a perspective view of the combined door and frame structure taken from a point rearwardly of and downwardly to the left of the rearwardly facing rear surface of the door and frame structure.

FIG. 3 is a horizontal cross-sectional view of the combined door and frame structure shown in FIGS. 1 and 2 taken along the line 3—3.

FIG. 4 is a horizontal cross-sectional view of the combined door and frame structure shown in FIGS. 1 and 2 taken along the line 4—4.

FIG. 5 is a vertical cross-sectional view of the combined door and frame structure shown in FIGS. 1 and 2 taken along the line 5—5.

FIG. 6 is a vertical cross-sectional view of the combined door and frame structure shown in FIGS. 1 and 2 taken along the line 6—6.

FIG. 7 is a horizontal cross-sectional view of the combined door and frame structure shown in FIGS. 1 and 2 taken along the line 7—7.
